NAILING ATTACHMENT FOR PNEUMATIC HAMMERS

Paul Van Sittert, Shaker Heights, and William E. Barth, Vermilion, Ohio, assignors, by mesne assignments, to Reed Roller Bit Company, Houston, Tex., a corporation of Texas

Application September 7, 1945, Serial No. 615,042

4 Claims. (Cl. 1—46.1)

1

This invention relates to improvements in percussive tools, more particularly those for driving nail sets and comprising guides or guards to assist the operator in holding the tool upon the head of a nail to be driven.

One of the objects of the invention is the provision of a tool of this character of simple construction and correspondingly low cost.

Another object of the invention is the provision in a tool of this character of guard means which may be mounted directly upon the nail set in such manner as to be readily assembled upon or removed from the set.

Other objects and features of novelty will appear as we proceed with the description of those embodiments of the invention which, for the purposes of the present application, we have illustrated in the accompanying drawing, in which

Fig. 1 is a fragmental elevational view of a percussive tool equipped with a nail set according to the present invention.

Fig. 2 is a longitudinal sectional view taken substantially on the line 2—2 of Fig. 1 and showing the condition of the tool at the stage at which a nail has been driven down flush with the work.

Fig. 3 is a cross-sectional view on a larger scale, taken substantially on the line 3—3 of Fig. 2.

Fig. 4 is a view similar to that of Fig. 1, showing a modified form of the invention.

Fig. 5 is a longitudinal sectional view on the line 5—5 of Fig. 4, but with the end of the guard flush with the end of the nail set as it would be at the completion of a nail driving operation, and

Fig. 6 is a detail sectional view taken substantially on the line 6—6 of Fig. 4.

In the drawing we have illustrated at 10 a fragment of the casing of a percussive tool having a cylinder 11 in which a reciprocating hammer 12 is movable by compressed air or other power means. In axial alignment with the cylinder 11 there is a bore 13 of somewhat smaller diameter flared at its outer end, in which is slidably mounted the inner portion 14 of a nail set disposed to receive blows from the hammer 12. The casing of the tool also comprises a cup-shaped extension 15 which is threaded onto the reduced end portion 16 of the larger part of the casing. The inner end of the cup 15 is split by a slot 17 which extends through a thickened part 18 of the rim of the cup. This thickened part is drilled tangentially and threaded to receive a screw 19 by means of which the split parts of the cup may be drawn together for tightly locking the cup to the principal part 10 of the casing.

Within the cup there is disposed a rubber block 55 may be identical with those of Figs. 1, 2 and 3.

2

20 with a central opening in which is received the outer constant diameter part 21 of the nail set, the base of the cup also having a bore 22 therethrough aligned with the opening in block 5 20 and with the bores 13 and 11 of the tool. A collar 23 on the nail set engages the inner end of the rubber block 20.

Around the constant diameter portion 21 of the set outward of the cup 15 there is mounted 10 a guide or guard 24 of sleeve form, these two parts being freely slidable with respect to each other. The set 21 has two oppositely disposed grooves 25 formed therein approximately semi-circular in cross-section and of limited length as 15 shown, these two grooves receiving steel balls 26, the outer portions of which extend into circular holes 27 in the guard 24. The holes 27 merge with a shallow groove 28 surrounding the guard 24, and in this groove there is a split spring ring 20 29 which retains the balls.

As will be apparent, these parts permit a certain limited relative movement longitudinally between the set and the guard. A coil spring 30 surrounding the set 21 bears at one end against the cup 15 and at the other end against the guard 24, the latter being preferably counterbored to receive the spring, the upwardly projecting rim 34 of the guard constituting a stop to limit the movement of the cup and guard toward each other.

30 In Fig. 2 we have shown a nail N driven into the workpieces 32 and 33, and have shown the condition of the tool at the time when the final blows are delivered.

When it is desired to remove the guard 24 the 35 operator, with the aid of a pointed instrument, springs the ring 29 out of its groove 28 and moves it lengthwise of the guard far enough to completely clear the groove, when the balls 26 may be permitted to fall out of the holes 27, thus freeing 40 the guard 24 from the set. In assembling the guard upon the set the guard is first slid into place and held substantially in the position of Fig. 2 against the action of the spring 30, the guard being turned to align the holes 27 with the 45 groove 25. Then the balls are inserted into the holes 27 and caused to extend into the grooves. The split ring 29 is then moved along until it rests within the groove 28, thereby locking the balls in operative position.

50 In the modification illustrated in Figs. 4, 5 and 6, the cup 35 corresponds to the cup 15 of the above described form of the invention, and nail set 41 corresponds to set 21. The internal parts of the tool not illustrated in Figs. 4, 5 and 6

A guard 44 is mounted upon the set 41 for relative sliding movement, being urged outwardly upon the set by a coil spring 50 which surrounds the set between the cup 35 and the guard. Guard 44 is shaped approximately like a sleeve, but is open on one side for a portion of its length as indicated at 51, and in line with this opening the bore of the sleeve is enlarged somewhat as shown at 52 in Fig. 5. At the outer end of the enlargement 52 there is a groove 53. An annular groove 54 in the set 41 receives a spring ring 55 having a pair of outwardly projecting ends 56. This ring, as it travels up and down, bears against the bore enlargement 52, and when it strikes the upper end of this enlargement it stops further movement of the guard outwardly upon the set.

In case it becomes desirable to remove the guard 44 in servicing the tool the operator pushes the guard inwardly against the action of the spring 50 until the groove 53 comes opposite the ring 55. He then spreads the ends 56 of the ring to cause the ring to leave the groove 54 and enter the groove 53, after which the guard may be pulled off the set 41. The reverse procedure is followed in assembling the guard upon the set.

In the foregoing description we have necessarily gone somewhat into detail in order to explain fully the particular embodiments of the invention herein illustrated, but we desire it to be understood that such detailed disclosures are not to be construed as amounting to limitations, except as they may be included in the appended claims.

Having thus described our invention, we claim:

1. In a percussive tool of the character described, a casing, a reciprocatory hammer therein, a nail set extending into said casing in line with said hammer to receive blows therefrom, said set having a cylindrical portion of uniform diameter projecting beyond the casing, a guard on the projecting uniform diameter portion of said set, said guard having a uniform bore slidably fitting said projecting portion, spring means for biasing said guard outwardly on said set, said set having a longitudinal groove, said guard having a radial opening adapted to register with said groove, and a detent held in said opening and movable in said groove for limiting outward movement of the guard.

2. In a percussive tool of the character described, a casing, a reciprocatory hammer therein, a nail set extending into said casing in line with said hammer to receive blows therefrom, said set having a cylindrical portion of uniform diameter projecting beyond the casing, a guard on the projecting uniform diameter portion of said set, said guard having a uniform bore slidably fitting said projecting portion, a coil spring surrounding said set between said casing and said guard for biasing the guard outwardly on the set, said set having a longitudinal groove, said guard

having a circular opening adapted to register with said groove, a detent in said opening and movable in said groove for limiting the outward movement of the guard, and means for holding said detent in operative position including a spring ring carried by said guard over said detent, which ring when withdrawn permits removal of said detent to enable the guard to be withdrawn from the set.

10 3. In a percussive tool of the character described, a casing, a reciprocatory hammer therein, a nail set extending into said casing in line with said hammer to receive blows therefrom, said set having a cylindrical portion of uniform diameter projecting beyond the casing, a guard on the projecting uniform diameter portion of said set, said guard having a uniform bore slidably fitting said projecting portion, a coil spring surrounding said set between said casing and said 15 guard for biasing the guard outwardly on the set, and cooperating means on said set and guard for limiting the outward movement of the guard, said cooperating means comprising a spring ring which when withdrawn permits said cooperating means to be disassembled to enable the guard to be withdrawn from the set.

20 4. In a percussive tool of the character described, a casing, a reciprocatory hammer therein, a nail set extending into said casing in line with said hammer to receive blows therefrom, said set having a cylindrical portion of uniform diameter projecting beyond the casing, a guard on the projecting uniform diameter portion of said set, said guard having a uniform bore slidably fitting said projecting portion, spring means for biasing said guard outwardly on said set, said set having a longitudinal groove, said guard having a circular opening adapted to register with said groove, and a ball held in said circular opening and movable in said groove for limiting the outward movement of the guard.
